MAKING INSOLES

Ross H. Johnson, Indianapolis, Ind.

Application November 29, 1943, Serial No. 512,217

3 Claims. (Cl. 12—146)

1

My invention relates to the method of making insoles for shoes which include an insole formed of thin cellular or sponge rubber or a similar material having a soft body which is adapted to form the inner portion of the insole.

A feature resides in cutting the insole out of a single piece of sponge rubber while the sponge rubber is held compressed within a die so that when the sponge rubber is released from the die, the insole is formed and merely requires a finishing top and bottom surfacing covering. It is also a feature of my insole to provide a means of detachably securing the same in the shoes of the wearer, thereby providing the advantage of the insoles being changed from one pair of shoes to another whenever it is desired.

It is a feature to provide an insole with an inner soft flexible body portion which is preshaped to the wearer's foot and the body of which is soft and yet active to stimulate the action of the muscles and circulation in the foot by compressing and expanding as the insole is walked on by the wearer, thus causing the muscles in the foot to function rather than be subjected to a hard or rigid flat insole in a shoe.

A further feature resides in making an insole wherein the inner body is formed of sponge rubber and in which the same is a single piece to form a heel cushion, a longitudinal and a metatarsal arch support for the foot, all formed in a single piece of sponge rubber to provide a resilient flexible body for the insole.

In making my insoles in the manner which will be more fully hereinafter set forth, I provide a single piece insole having the several features of the heel cushion, the longitudinal arch support and the metatarsal arch support, all in a single insole, or I may provide the same in a combination of the metatarsal support associated with a heel cushion support or in the form where metatarsal arch supporters are provided.

It is also an important feature to provide an insole which is made by slicing or cutting the same from a died out form of sponge rubber which is held under the die by compression while it is being cut in the desired shape in accordance with the shape of the die in a simple and inexpensive manner. This method does not require heat moulding of the insoles but is rather carried out by a cold process which is quickly accomplished in an economical manner.

In the drawings forming a part of the specification:

Figure 1 is a perspective view of my insole in

2

which the heel cup, longitudinal and metatarsal arch supports are formed.

Figure 2 illustrates another form of my insole where a metatarsal support is formed.

5 Figure 3 illustrates still another form where the metatarsal and longitudinal arch supports are formed therein.

Figure 4 is the bottom portion of Figure 1 showing the attaching means for the insole.

10 Figure 5 is a section on the line 5—5 of Figure 1.

Figure 6 is a section on the line 6—6 of Figure 1.

15 Figure 7 is a section on the line 7—7 of Figure 1.

Figure 8 is a perspective view of the portion of the die apparatus for forming my insoles out of sponge rubber or the like showing the cover die in open position.

20 Figure 9 shows the die for forming the insoles closed and in the position it would assume at the finishing stroke of cutting one of my insoles.

Figure 10 is a detailed section of a portion of the die shown in Figures 8 and 9.

25 My insole A is formed with a body portion 10 of sponge rubber. In making the insole the sponge rubber of a pre-determined thickness is died out in the outline shape of the insole such as shown in Figures 1, 2 and 3. The died out form

30 of the thick sponge rubber sheet is also shown by the opening for receiving the died out insole shown in the center die member 12 and is adapted to be supported in the die-head 13. The died out formation in the member 12 is illustrated by the opening 11 in the die 12.

35 After the died out body 10 is placed in the die opening, the cover member 14 of the die-head which carries the top die member 15 is closed and locked by the lever 16 which has a tongue end 17

40 which projects over the free edge of the cover 14 to hold the cover closed with the die member 15 compressed into the sponge rubber body 10 as illustrated in Figure 10.

45 The die-head 13 is adapted to support the lower die member 18 which is positioned in the bottom of the die-head.

When the cover 14 is closed, as illustrated in Figures 9 and 10, by the lever 16, the sponge rubber body 10 is compressed into the lower die 18.

50 Thus, the sponge rubber body 10 is held compressed by the die members 16 and 18 in the opening 11 of the die-head.

The die-head 13 is slideably supported in the guides 19 so that the die-head 13 may be slid in the direction of the arrow shown in Figures 9 and

10 against the operating endless knife 20 (only a portion of which is shown). The knife 20 operates at a high speed and is kept very sharp on the edge 21 so that as the die-head 13 with the sponge rubber body 10 is moved toward the knife 20, the knife will slice through the sponge rubber body cutting the same to form the insole A. It is desirable that the insole body 10 be immersed in water before it is inserted in the die-head 13 so that when the die-head is operated against the knife the water will form a lubricant to permit the knife 22 to make a clean cut through the body 10 to form the insole A with the desired thickness. After the insole has been formed out of the body sponge rubber 10 and the cover 14 is raised, the insole is formed complete ready to be finished with top and bottom members for covering the rubber body of the insole. The dies 15 and 18 shape the insole A so that it is straight along the bottom and is provided with the elevations 22, 23 and 24 which form respectively the metatarsal arch, the longitudinal arch, and the heel cup as illustrated in Figures 1, 5, 6 and 7.

The making of the insole A is completed by securing a thin sheet of leather 25 or other similar material to the top of the rubber body 10 of the insole. Then a body sheet 26 of cloth or other material is attached to the bottom of the insole after which a longitudinal adhesive strip 27 is applied along the bottom of the insole A. It is desirable that the adhesive strip 27 be formed with adhesive material on both sides so that one surface may be adapted directly to the bottom of the insole while the other surface is covered with a removable strip 28 to protect the outer adhesive surface of the strip 27 until it is desired to attach the insole A to the insole of a shoe. Thus, the insoles A may be sold to the customer with a strip 28 covering the adhesive of the securing strip 27, and then all the customer needs to do is remove the strip 28 as illustrated in Figure 4 and place the insole in the shoe, whereupon the pressure of the foot will cause the strip 27 to secure the insole in the proper place. If the user of the insoles wishes to remove the insoles A, he may do so at any time by carefully lifting the insole, starting at the heel of the insole and removing the insole from the shoe, whereupon the strip 27 may still provide a means of attaching the insole A into another pair of shoes. The adhesive material 29 on either side of strip 27 is of a non-drying character and remains to hold the insole in proper position in the shoe. Thus, the strip 27 provides the means of removably supporting the insole A within the shoe.

The guide members 19 are formed with slots through which the knife 20 slides to permit the die-head 13 to be moved toward the cutting edge of the knife in the operation of cutting the insole A. This operation of cutting an insole is very simple and may be quickly accomplished by the knife 20 slicing the compressed rubber body 10 to form the same in the desired shape with the projecting surfaces as illustrated in the various figures in accordance with the shape of the surface of the dies 15 and 18.

The die 12 may be removed and reversed so as to receive a right or left hand insole as the case may be. In the same manner, the dies 15 and 18 may be removed and replaced by right or left hand dies as may be desired.

Therefore, it is apparent that with my means of making an insole that I believe I have accom-

plished a new manner of easily forming an insole in the desired shape which may be used in a person's shoes to cushion the sole of the foot, support the metatarsal arch, as well as the longitudinal arch, and provide a heel cup to provide a soft flexible insole which will shape itself to the foot and provide a means of exercising the muscles owing to the sole fitting formation of the innersole and to the compressible and expandable nature of the insole.

It is not necessary to cover the bottom of the sponge rubber body of the insole. However, it is desirable that the top should be covered with a thin flexible piece of smooth-faced material so that the wearer's foot will slip easily into the shoe. The bottom of the insole may be uncovered except for the longitudinal adhesive attaching strip which has a non-drying adhesive surface for attaching the insole to the shoe.

I have also found that my insoles may outlast the wear of the ordinary shoes and, therefore, it is desirable to remove the same and put these insoles in the new pair of shoes if the wearer desires. Furthermore, the wearer may change the insoles from one pair of shoes to another whenever he desires.

In my insoles it is possible to take the impression of anyone's foot with any suitable moulding material. Then this mould is used as a die to form the body of the insole by cutting or slicing the same from a block of material as hereinbefore set forth to provide an insole which fits each individual's foot. Furthermore, the making of these insoles may be done economically and in a comparatively short time.

A further feature resides in securing the top material such as leather or other facing materials to the sponge rubber before it is died out, thus when the machine slices out the insole, it is complete and ready for use. This method of attaching the facing material for the top of the insole is of primary importance in making insoles economically and it reduces operations and increases the speed of production.

I claim:

1. The method of making an insole for shoes, which comprises slicing the same from a block of sponge rubber while it is compressed between upper and lower dies, which dies are formed into the desired shape to provide metatarsal and longitudinal arch supporting means and a heel cup socket.

2. The method of making an insole for shoes, comprising forming a soft spongy body portion by slicing the same from a block of material while compressed between die means, thereby forming the body of the insole in a single slice from the block and covering the top of the sponge body insole with a sheet of thin leather and securing a strip of two-faced non-drying adhesive with an outer removable covering longitudinally to the bottom of said insole for removably attaching said insole in the wearer's shoe.

3. The method of making an insole for shoes, consisting in slicing the same from a block of sponge-like material while it is compressed between upper and lower dies, which dies are formed into the shape of an individual's footprint to provide metatarsal, longitudinal arch, and heel supporting means shaped to the exact impression of an individual's foot.
